UNITED STATES PATENT OFFICE.

SAMUEL C. MCCLURE, OF DAYTON, OHIO.

DESIGN FOR AN ADVERTISING-CARD.

SPECIFICATION forming part of Design No. 19,297, dated September 3, 1889.

Application filed July 18, 1889. Serial No. 317,948. Term of patent 14 years.

To all whom it may concern:

Be it known that I, SAMUEL C. MCCLURE, a citizen of the United States, residing at Dayton, in the county of Montgomery and State of Ohio, have invented and produced a new and original Design for Advertising-Cards, of which the following is a specification, reference being had to the accompanying drawing, forming a part thereof, and in which—

10 The single figure represents a plan view of an advertising-card embodying my improved design.

The leading feature of my design for advertising-cards consists in a large rectangular figure, within and extending parallel with the marginal lines of which are a series of square figures, each series of said square figures at the horizontal (top and lower) sides of the large rectangular figure being separated from the series of similar figures along the vertical sides of said large rectangular figure by intervening rectangular spaces, and all of said square figures being so disposed as to leave a rectangular space in the center of the large rectangular figure, and a series of oblong or rectangular figures located above the large rectangular figure and one above the other and in parallel planes with relation to each other.

30 A designates the rectangular card, upon which are inscribed the large rectangular figure A' and a series of oblong figures B, C, and D, which are located above said figure A' and above one another. The intermediate oblong figure C is longer and wider than the other two figures B D, and all of said figures B C D are arranged in parallel horizontal planes.

40 Within the marginal lines of the large rectangular figure A', and extending around the sides thereof, are a number of square figures, which are divided into four series E F G H.

The series of square figures E G along the horizontal sides of said rectangle A' are separated or divided from the series F H of similar-shaped figures by dividing-lines *a b*, thus providing an open blank rectangular space I between the intersection of each of the series of square figures. The square figures composing each horizontal series of figures E G are separated from each other by parallel division-lines *j j'*, which form an intervening oblong space J between two adjoining figures of the horizontal series of figures E and G. Each of the square figures of each series are divided by a series of horizontal and vertical lines K K', respectively. The square figures of each of the series E F G H are equal in width and arranged parallel with the sides of the rectangle A', so as to provide a rectangular space L in the center of the rectangle A.

It is obvious that the square figures are especially adapted to receive the data and figures of the calendar months, while the spaces I, J, and L are adapted to receive advertisements or advertising-cards or other matter.

What I claim is—

The design for an advertising-card herein shown and described, the same consisting of a rectangular figure A', the series of square figures E F G H, located within said rectangular figure, near the marginal lines thereof, to form a central space L, the rectangular spaces I, located between the series of said square figures near the angles or corners of the large rectangular figure, and the oblong spaces J, as described.

In testimony whereof I affix my signature in presence of two witnesses.

SAMUEL C. MCCLURE.
